JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 20, 1923. Serial No. 626,282.

This invention relates to typewriting machines and more particularly to mechanism for typing upon printed forms.

When a mail-order or other house receives an order, it is copied on a uniform invoice form. Usually the articles are grouped in different departments; and, in order to enable a number of these different departments to work on several parts of an order simultaneously, the original order is split up in the copying, that is, it is typed upon as many separate forms as there are different items in the order. For instance, if the original order calls for a dozen pairs of shoes, six hats and four suits of clothes, the typist will use three separate forms, all bearing the same serial order number, one containing the shoe item to be given to the shoe department for execution, one containing the hat item to be given to the hat department, and one containing the suit item to be given to the clothing department. Later these forms, together with the articles they call for, are sent to the shipping department, the goods are identified by their order numbers, assembled and packed.

It will be seen that, if only the items calling for like articles are typed on a single form, there will only be a few lines of typed matter on each separate form. One of these lines of typing will be on the heading and the other several line-spaces lower in the body of the form. It will also be seen that if the forms were printed on separate sheets of paper, much time would be consumed in inserting the form, bringing the first writing line to the printing point by line-spacing, line-spacing again to bring the second writing line to the printing point, extracting the form and inserting another. Where there are hundreds of these forms to be typed every day, it will be appreciated that the time loss is very great.

My invention permits the printing of the invoice forms on a continuous work-sheet that may be rolled on a spool or folded in zigzag fashion on the dividing lines that separate the forms. The forms may be separated from one another by weakened lines or perforations, or may be left plain with their lines of detachment indicated by registration marks. During the entire operation that completes a plurality of these forms, the regular line-spacing mechanism of the typewriter need only be employed to advance

the work-sheet from the first to the second writing lines on the forms, and at all other times the much quicker method of advancing the work-sheet, by drawing it out of the machine with the fingers, may be used. My invention also provides mechanism for gaging the leading form on the work-sheet, after that form has been completed, for severing that form from the work-sheet, simultaneously with the bringing of the first writing line of the second form to the printing point. It is this dual gaging operation that is responsible for the greater part of the saving in time.

Other features and advantages will hereinafter appear.

In the accompanying drawings, Figure 1 is a plan view of a typewriter-carriage, showing my invention attached thereto.

Figure 2 is a front elevation of the machine shown in Figure 1.

Figure 3 is a partial sectional view of a typewriter with my invention attached thereto.

Figure 4 is a detail view of the end of the carriage of a typewriter to which my invention has been attached, showing the position of the detent-lever with relation to the line-space ratchet-wheel when my invention is being used.

Figure 5 is a detail perspective view of a paper-guide which is part of my invention.

Figure 6 is a diagrammatic view of the leading edge of a continuous work-sheet bearing printed invoice forms.

A platen 7 is mounted on a platen-shaft 8, which is journaled in a movable carriage 9. Line-spacing mechanism, which includes an actuating pawl 10 mounted on a line-space slide 11, which is actuated by the usual line-space lever, not shown, is mounted on the end of the carriage to actuate a line-space ratchet-wheel 12 fastened to the platen-shaft 8. A detent-releasing lever 13 having a finger-piece 14 is loosely mounted on the platen-shaft 8 to displace a detent lever 15, whose detent roller 16 is normally held in engagement with the teeth of the ratchet-wheel 12 by a spring 17. The usual lever and sliding cam mechanism is employed which determines the number of line-spaces the platen may be rotated by a single thrust of the slide 11. Feed-rolls 18 and 19 co-operate with a rear paper-table 20 in feeding

work-sheets underneath and around the platen 7. Mounted on the back of the rear paper-table 20, near its side edges, are brackets 21 which support a transverse paper-gage 5 shaft 22. Right and left paper-gages 23, which have flat bodies 24, upstanding edges 25 and retaining ears 26, are positioned on the rear paper-table 20. The bodies 24 of the paper-gages 23 extend backwardly and 10 downwardly around the upper edge of the rear paper-table 20. These body-extensions 24 have formed thereon ears 28 which are hinged to slides 29 which are movably mounted on the shaft 22. This connection 15 permits the paper-gages 23 to be adjusted transversely of the rear paper-table 20, and also to be swung upwardly and backwardly out of the way when not in use.

Journaled in the ends of the carriage 9 20 is a transverse table-supporting shaft 30. Movably mounted near the ends of the shaft 30 are table brackets 31 which carry a transverse table bar 32. The upper ends of the 25 table-brackets 31 have slots 33 formed there- in to engage a transverse shaft 34 which is supported on the carriage 9 by brackets 35. The lower ends of the table-brackets 31 have 30 projecting arms 36 which carry rollers 37 which rest on the platen 7. Adjustably mounted on the table bar 32 is a front paper-table 38 which has upstanding side guides 39 formed thereon. Mounted near the top 35 of the front paper-table 38 is a combined gage and web-severing knife 40 so formed that the cutting edge 41 is positioned close to the table surface, while the rear edge 42 is raised from the table surface to facilitate the rapid insertion of a work-sheet underneath the knife 40. It will be seen, when 40 pressure is brought to bear on the upper edge of the front paper-table 38 while severing a work-sheet, that the upper ends of the brackets 31 will be restrained by the transverse shaft 34 to minimize that pressure, and that the bearing of the arms 36 45 against the platen 7 will still further counteract that pressure. This construction, while not obligatory, is the preferred one for my invention, and provides a rigid support for the front paper-table 38.

Mounted on the carriage 9, in front of the platen 7, is a curved guide-finger 43 which, when swung into operative position, is fastened to prevent bulging or bowing of the 50 work-sheet away from the front paper-table 38.

All of the mechanism heretofore described is mounted to move transversely of the machine with the platen 7 and the carriage 9 55 on rails 44 and 45.

Mounted on the rear of the frame of the machine are brackets 46 which support a rail 47. Riding on rollers 48 on the rail 47 60 is a paper-spool carrier 49, whose front end is hinged by means of links 50 to a shaft

51 supported in brackets 52 fastened on the back of the rear paper-table 20. In operation, this mechanism will move transversely of the machine with the other mechanism described and with the carriage 9. Mounted 70 on a pin 53 is a paper-spool 54 in which is wound a work-sheet 55. The work-sheet 55 has printed thereon a plurality of invoice forms 56 separated from one another by lines of detachment 57. Writing lines, 75 such as 58, 59 and 60, are indicated on the forms 56. The writing lines 58, 59 and 60 may be one line-space or more apart, as is desired.

In operation, the typist places the paper-spool 54, on which is wound the work-sheet 55, in the carrier 49. The paper-gages 23 are set to register with the side guides 39. The leading edge of the work-sheet 55 is then threaded over the top of the rear paper-table 20, over the paper-gages 23 in a manner to confine the edges of the work-sheet 55 beneath the retaining ears 26, underneath and around the platen 7 and over the previously released feed-rolls 19 and 18, and up 80 the front of the platen and over the front paper-table 38 between the side guides 39, and is inserted under the raised rear edge 42 and made to register with the cutting edge 41 of the knife 40. The guide-finger 43 is 85 now swung to operative position in front of the work-sheet 55. The first writing line 58 of the first printed form 56 is now opposite the printing point. In this instance it is 90 assumed that the writing line 59 is three line-spaces below the writing line 58 on the form 56, and that these two writing lines are the 95 only ones to receive typed matter, so that the typist sets the usual sliding cam lever of the line-space mechanism at the figure "3" on 100 the scale, and moves the detent-release lever 105 105 110 115 120 125 130 135 140 145 150 155 10105 10110 10115 10120 10125 10130

From this description, it will be seen that the knife 40 becomes a guide to prevent the work-sheet from falling forwardly, a gage to co-operate with the spaced-off work-sheet and a severing element to promote tearing off the finished section; that during the printing and severing operations, the web is under the control of the two feed-rolls 18 and 19; that during the operation of drawing the web to the severing position, the feed-rolls are cast off and the web may be quickly and freely drawn around the platen face between rear and front lateral guides that coact to square the web to the cutting edge of the knife; and that during the cutting off operation, the front table 38 provides a hand-rest where hand pressure may be applied against the face of the unsevered web to promote a square severance of the finished work-sheet section.

It will be noticed that the typist, after threading the work-sheet 55 through the machine, has to make only three work motions, besides the regular typing motions, in order to complete a form 56, the first to return the carriage 9 and bring the second writing line 59 to the printing point, the second to gage the first form 56 to sever it and bring the first writing line 58 of the succeeding form 56 to the printing point, and the third to sever the first form 56.

It is understood, of course, that, in practice, a plurality of superimposed work-sheets interleaved with carbons may be fed through the machine in the same manner, thus producing a plurality of copies of each form for various uses, and that forms other than invoice forms, that may have a plurality of writing lines instead of only two, may be printed on those work-sheets.

Variations may be resorted to within the scope of the invention, and portions of the improvements may be used without others.

Having thus described my invention, I claim:

1. In a typewriting machine, in combination, a revoluble platen, feeding means to feed a continuous work-sheet which may bear a plurality of similar printed forms separated by lines of detachment, underneath and around said platen, adjustable gaging means to gage said work-sheet laterally on the entry side of said platen, said gaging means comprising right and left paper-gages having upturned outer side edges with retaining ears to retain the edges of said work-sheet, adjustable supporting means, which includes lateral work-sheet guides, to support said work-sheet on the delivery side of said platen, movable guiding means to guide said work-sheet over said supporting means, and a combined gaging and severing means mounted on said supporting means to gage said work-sheet longitudinally.

2. In a typewriting machine, in combination, a revoluble platen, feeding means to feed a continuous work-sheet which may bear a plurality of similar printed forms separated by lines of detachment, underneath and around said platen, adjustable gaging means to gage said work-sheet laterally on the entry side of said platen, said gaging means comprising right and left hinged paper-gages mounted to be adjustable transversely of the machine with upturned outer side edges and retaining ears, adjustable supporting means, which includes lateral work-sheet guides, to support said work-sheet on the delivery side of said platen, movable guiding means to guide said work-sheet over said supporting means, and a combined gaging and severing means mounted on said supporting means to gage said work-sheet longitudinally.

3. In a typewriting machine, in combination, a revoluble platen, feeding means to feed a continuous work-sheet which may bear a plurality of similar printed forms separated by lines of detachment, underneath and around said platen, adjustable gaging means to gage said work-sheet laterally on the entry side of said platen, adjustable supporting means to support said work-sheet on the delivery side of said platen, said supporting means comprising a paper-table having sections of its side edges upturned to form lateral work-sheet guides, other sections extended laterally to form ears adjustably secured to the table, movable guiding means to guide said work-sheet over said paper-table, and a combined engaging and severing means mounted on said paper-table to gage said work-sheet longitudinally.

4. In a typewriting machine, in combination, a revoluble platen, a movable carriage to carry said platen, work-sheet carrying means mounted to move with said carriage to carry a rolled continuous work-sheet, feeding means to feed said work-sheet underneath and around said platen, adjustable supporting means, which includes lateral work-sheet guides, to support said work-sheet on the delivery side of said platen, movable guiding means to guide said work-sheet over said supporting means to confine said work-sheet within said lateral work-sheet guides, and a combined gaging and severing means to gage said work-sheet on the delivery side of said platen and to sever the leading work-sheet section.

5. In a typewriting machine, in combination, a revoluble platen, a movable carriage to carry said platen, work-sheet carrying means mounted to move with said carriage to carry a rolled continuous work-sheet, feeding means to feed said work-sheet underneath and around said platen, adjustable gaging means to gage said work-sheet on the entry side of said platen, adjustable sup-

- porting means, which includes lateral work-sheet guides, to support said work-sheet on the delivery side of said platen, movable guiding means to guide said work-sheet over 40
5 said supporting means to retain said work-sheet within said lateral work-sheet guides, and gaging and severing means to gage said work-sheet longitudinally and for severing a work-sheet section therefrom.
- 10 6. In a typewriting machine, in combination, a revoluble platen, a movable carriage to carry said platen, work-sheet carrying means mounted to move with said carriage to carry a rolled continuous work-sheet, 45
15 feeding means to feed said work-sheet underneath and around said platen, adjustable gaging means to gage said work-sheet on the entry side of said platen, printing devices to type matter on said work-sheet, line- 50
20 spacing mechanism to advance said work-sheet, adjustable supporting means, which includes lateral work-sheet guides, to support said work-sheet on the delivery side of said platen, movable guiding means to guide 55
25 said work-sheet over said supporting means to retain said work-sheet within said lateral work-sheet guides, and a combined gaging and severing means to gage said work-sheet longitudinally and sever a work-sheet section.
- 30 7. In a typewriting machine, in combination, a revoluble platen, a movable carriage to carry said platen, work-sheet carrying means mounted to move with said carriage to carry a rolled continuous work-sheet, 60
35 feeding means to feed said work-sheet underneath and around said platen, adjustable gaging means to gage said work-sheet on the entry side of said platen, printing devices to type matter on said work-sheet, line-spacing mechanism to advance said work-sheet a predetermined number of line-spaces, means to actuate said line-spacing mechanism simultaneously with the returning of the carriage, adjustable supporting means, which includes lateral work-sheet guides to register and co-operate with said adjustable gaging means, to support said work-sheet on the delivery side of said platen, movable guiding means to guide said work-sheet over 65
40 said supporting means to retain said work-sheet within said lateral work-sheet guides, and a combined gaging and severing means to gage and sever said work-sheet longitudinally.
8. In a front-strike typewriting machine, the combination with a platen, of introductory side guides for a work-web, and a web-guiding and web-severing table at the delivery side of the platen, and provided at its upper edge with a web-severing and web-gaging knife juxtaposed to the table to co-operate therewith to form a guide for the web, said table extending down from said knife to the platen, side guides for the web being provided on said table between said platen and said knife and co-operative with the introductory side guides to keep the web true when the feed rolls are cast off and the web is pulled up rapidly by hand to be torn off by means of said knife; said knife in position to sever the last-typed form, and forming a gage positioning the web for the first line of typing on the next form. 70
